UNITED STATES PATENT OFFICE.

EDMUND OGLE, OF DAWSON, NEBRASKA.

WRENCH.

Application filed March 10, 1925. Serial No. 14,482.

This invention relates to an improved tool or automotive appliance which may be referred to as a wrench, the same being especially, but not necessarily, designed for removing automobile lens clamping rims.

It is my principal aim to improve upon devices of this class by providing one of comparative simplicity and durability which embodies a novel arrangement of details and parts capable of producing an exceeding practical and inexpensive structure.

The features and advantages derived from the particular structural details employed will become apparent from the following 15 description and drawing.

In the accompanying drawings forming a part of this application, and in which like numerals are employed to designate like parts throughout the same:

20 Figure 1 is an elevational view of portions shown in section, of a lens wrench constructed in accordance with the present invention.

25 Figure 2 is an enlarged detail view thereof showing the structure incomplete, but more clearly.

Referring to the drawings in detail, it will be seen that the reference character 1 designates a handle, the same having one 30 end shaped as at 2 to provide a comfortable hand-grip. The handle might be constructed otherwise, but it is preferably formed from a sheet of metal bent to provide a channel. Fastened by a removable bolt 3 in the 35 channel at the opposite end thereof is one end of a flexible friction grip belt or band 4. Pivoted as at 5 to the side flanges of the channel shaped handle is a correspondingly shaped clamping member 6. The cross section of this member 6 is such as to permit the handle 1 to be telescoped between its side flanges. The member 6, like the handle 1 has its outer end fashioned as at 7 to provide an additional hand grip. At the pivoted 40 end of the member 6, a portion of the metal is struck out as at 8 to provide a guide tongue and the free end portion 9 of the band is adapted to contact this tongue and to pass into the channel 6 with its extremity 50 clamped between the laterally directed

toothed portion 9 of the retaining bracket 10.

In practice, the flexible band 4 is placed around the rim 11 of a headlight lens 12 and the free end portion 9 is passed into the channel shaped member 6, the extremity of 55 the same being tightly clamped between the channel member and the teeth of the bracket 10. The member 6 has its upper end open to permit access to be had to the free end of the band in drawing it between the bracket 60 and the clamping member. In this way the band can be adjusted to accommodate any diameter of clamping rim, and when it is pulled sufficiently tight, an effective grip will be had upon the rim which will be sufficient 65 to enable the user to turn the rim to remove it.

Although this invention has been described as being particularly adapted for use in removing the clamping rims of automobile headlight lenses, it is to be understood that it may be used for any other purpose where a wrench of this kind is desirable, for instance, it may be employed, when made on a smaller scale, as a wrench for removing the covers of jars and the like. Furthermore, although the particular embodiment of the invention has been shown and described it is to be understood that minor changes coming within the field of invention 80 claimed may be resorted to if desired.

Having thus described the invention, what I claim as new is:

A wrench of the class described comprising a handle, a flexible friction grip band attached at one end to one end of said handle, a substantially channel shaped clamping member pivoted at one end to an intermediate portion of said handle, the free end portion of said band being adapted for reception in the channel of said member, and a bracket carried by said handle and having a laterally directed end portion provided with teeth, said clamping member being adapted to bind said band against said teeth when the clamping member is moved toward the handle.

In testimony whereof I affix my signature.

EDMUND OGLE.
